UNITED STATES PATENT OFFICE

GIOVANNI RITOSSA, OF NEWPORT NEWS, VIRGINIA

TOP SPINNING HOLDER

Application filed January 13, 1930. Serial No. 420,556.

This invention relates to a top spinning device.

The object of this device is to provide a holder for a top to facilitate spinning of the same, comprising a receptacle in said holder in which the top is placed after the string is wound thereon.

Reference is had to the accompanying drawing in which:—

10 Figure 1 is a plan view of the top and holder, and

Figure 2 is an elevational view partly in section of the same.

The holder 10 is preferably made of wood 15 or any other suitable material and comprises a bowl 11 and handle 12, the whole being in the form of a conventional pipe. The bowl 11 is provided with a somewhat tapered recess 13 to serve as a receptacle for a top 14 20 of conventional design.

Formed centrally in the wall of the bowl 11 is an opening 15 through which is inserted one end of a string 16 prior to being wound on the top 14, the other end having attached 25 thereto a ring 17.

To spin the top, the string 16 is inserted through the opening 15 and wound on said top in the well known manner. The top is placed in the bowl 11 of the holder 10 which 30 is held in one hand. By pulling sharply on the string 16 with the other hand, the top will be caused to spin, the moving of the string 16 through the opening carrying the top upwardly which will jump out of the 35 bowl to continue its spinning on the ground, or any other selected surface.

While a preferred embodiment of top holder has been shown, the same is susceptible of various modifications within the scope of 40 the appended claims.

Having thus described my invention, what I claim as new and desire to secure by Letters Patent is:—

1. In a top spinning device, a holder comprising a bowl, a handle integrally formed therewith said handle and bowl forming a pipe-like unit, a recess in said bowl adapted to receive a top, a transverse opening in the wall of said bowl intermediate the top and bottom thereof, a top, said recess being larger

than the top whereby said top may spin freely therein while resting with its point on the bottom of the recess, a string inserted through said opening and adapted to be wound on said top within said bowl, said string remaining out of contact with the sides of said bowl, and a ring attached to the depending end of said string.

2. A spinning device comprising a pipe-bowl-shaped holder, a pipe-stem-like handle 60 integrally connected therewith, said holder having a recess adapted to receive a top, said recess being larger than the top whereby said top may spin freely therein while resting with its point on the bottom of the recess, 65 said holder having a transverse opening in its wall intermediate the upper and lower portions thereof to operatively receive a top spinning string therethrough to be wound on said top within said bowl.

In testimony whereof I affix my signature.
GIOVANNI RITOSSA.
